By J. M. Thomas

UNITED STATES PATENT OFFICE.

RULON H. DAVIS AND THERON C. TEEL, OF SALT LAKE CITY, UTAH.

TOY.

Application filed June 23, 1925, Serial No. 38,953.

Our invention relates to toys, and has for its object to provide a new and novel aeroplane appearing tricycle toy for children upon which a child may ride and direct by shifting the rear wheel.

These objects we accomplish with the device illustrated in the accompanying drawings in which similar letters and numerals of reference indicate like parts throughout the several views and described in the specification forming a part of this application and pointed out in the appended claims.

In the drawings in which we have shown the best and most substantial embodiment of our invention, Figure 1 is a side elevation of the toy. Figure 2 is a plan view of the same, parts cut away, and parts shown in dotted lines. Figure 3 is a front elevation of the device.

One of the objects we accomplish is to give the toy the appearance of an aeroplane by giving the body A of the toy the shape of an aeroplane when viewed from its side, and by attaching to the upper edge of said body a supporting board 1 on which the smaller toys of the child may be carried, and which board has the appearance of a plane on an aeroplane. A crank axle B is mounted for rotation by the bracket bearings C and D. The upper end portions of the said bearings C are fastened to the sides of said body A, and the central bearing D is fastened to the under side of said body. The two front wheels E are secured on and rotate with said axle B and foot pedals F are carried on said axle by which it is rotated. A miniature propeller G is mounted on the front end of said body A and which is rotatable by the force of the wind striking it when the toy is run over the ground. A rear wheel H is mounted under the rear end of said body by the bifurcated bearing support J which is pivoted in said body. A short lever 2 has one end fastened to said bearing support J by which the direction of said rear wheel is controlled. A handle standard K is vertically pivoted through said body A by the crank bolt 3 and on whose lower end portion is pivoted one end

of the connecting bar 4. The other end of said bar 4 is pivoted to the said lever 2, and said bar extends from the lever 2 on one side of the body A to the crank bolt 3 on the opposite side of said body. A depending pin 5 secured in the under side of said body A prevents the turning of said crank bolt 3 to a position which would bring the lever 2 and the crank portion of the bolt 3 on the same side of said body, as said position will prevent the desired guiding of the toy. A seat L is provided on said body for the child to sit on while operating the toy.

Having thus described our invention, we desire to secure by Letters Patent and claim:

In a toy of the class described the combination of a single thin body member having its lower edge on one plane and its upper edge cut on a sinuous line of three planes; a seat secured on the upper edge of the medial plane of said body member; a support board secured on the upper edge of the widest portion of the body member and at right angles to its vertical plane; a bifurcated wheel standard carried in the rear end portion of the body member; a wheel mounted between the bifurcated portion of said standard; a lever arm secured on the said standard and extending at right angles to said body member; a three bearing crank axle mounted under the front end portion of said body member; a wheel secured on each end of the crank axle; foot pedals carried on said axle for rotating it and spaced on opposite sides of the medial bearing on the crank axle; spaced apart bearing supports having their upper end portions secured to said body member; and their lower ends formed as bearings for said axle; a crank rod journalled in said body member; and a connecting bar pivoted to the lower end of said crank rod and to the lever arm of said rear wheel standard.

In testimony whereof we have each affixed our signatures.

RULON H. DAVIS.
THERON C. TEEL.
